(57) **CLAIM**

The ornamental design for floating gem jewelry, as shown and described.

DESCRIPTION

FIG. 1 is a front elevational view of a floating gem jewelry showing our new design, the rear and side views being a mirror image thereof;

FIG. 2 is a top plan view;

FIG. 3 is a bottom plan view;

FIG. 4 is a front elevational view of a floating gem jewelry showing a second embodiment of our new design, the rear and side views being a mirror image thereof;

FIG. 5 is a top plan view of FIG. 4; and,

FIG. 6 is a bottom plan view of FIG. 4.

It being understood that the broken lines are for illustrative purposes only and form no part of claimed design.
